CLAIM

The ornamental design for a sport utility auxiliary baggage carrier, as shown and described.

DESCRIPTION

FIG. 1 is a perspective view of a sport utility auxiliary baggage carrier, showing my new design;

FIG. 2 is a perspective view of the sport utility auxiliary baggage carrier, shown in a folded position;

FIG. 3 is a rear elevational view of the sport utility auxiliary baggage carrier of FIG. 1;

FIG. 4 is a top plan view of the sport utility auxiliary baggage carrier of FIG. 1;

FIG. 5 is a side elevational view of the sport utility auxiliary baggage carrier of FIG. 1; and,

FIG. 6 is a front elevational view of the sport utility auxiliary baggage carrier of FIG. 1.

The broken line showing a fragmentary view of a sport utility vehicle is for illustrative purposes only and forms no part of the claimed design.
